UNITED STATES PATENT OFFICE.

JAMES F. SWIFT, OF KANSAS CITY, MISSOURI.

DOOR-SPRING.

1,263,623.

Specification of Letters Patent. Patented Apr. 23, 1918.

Application filed December 15, 1916. Serial No. 137,116.

To all whom it may concern:

Be it known that I, JAMES F. SWIFT, a citizen of the United States, residing at Kansas City, in the county of Jackson and State of Missouri, have invented a certain new and useful Improvement in Door-Springs, of which the following is a specification.

My invention relates to improvements in door springs.

The object of my invention is to provide a novel spring mechanism, particularly adapted for use in closing doors, which is arranged so as to exert relatively great leverage power with a spring of minimum strength and size, which is economical to manufacture and easily attached to a door by an inexperienced person, which is not liable to get out of order, is durable, and which will readily swing the door when it has been swung to the fully open position.

My improved door spring is adapted to be substituted for the usual spring hinges and for the ordinary long coil spring which is commonly used for such purposes, and which is not adapted to close the door when the latter has been swung to the fully open position. Owing to its construction and to the manner in which it is attached to a door, a much weaker and smaller spring is required in my improved spring mechanism than is required in spring hinges or the usual long coil spring above referred to.

The novel features of my invention are hereinafter fully described and claimed.

In the accompanying drawing, which illustrates the preferred embodiment of my invention,

Figure 1 is an inside elevation of a portion of a door and its frame, having attached thereto my improved door spring mechanism.

Fig. 2 is a horizontal section on the line 2-2 of Fig. 1.

Fig. 3 is an enlarged horizontal sectional view on the line 3-3 of Fig 1.

Similar reference characters designate similar parts in the different views.

1 designates a hinge member adapted to be secured, as by screws 2, to the inner side and central portion of a door 3.

A swinging member 4 is pivoted to the member 1 by a vertical pintle 5. The swinging member 4 is preferably provided with two arms 6 disposed one above the other and having extending therethrough

a vertical pin 7. A connecting mechanism, preferably flexible, is attached to the pin 7 and to a door jamb 8 at the inner side of the door 3. This connecting mechanism 60 preferably constitutes a horizontal rod 9 having at one end a hook 10 which embraces the pin 7 intermediate of the arms 6, the hook preferably being open, as shown, to permit the ready detachment thereof from 65 the pin. The other end of the rod 9 is provided with a hook 11, which pivotally engages the apex of a V-shaped member 12 having hooked ends which respectively pivotally engage screw eyes 13 secured in the 70 adjacent jamb 8 at the inner side of the door 3.

Encircling the pin 7, preferably at both sides of the rod 9, between the arms 6, is a coil spring 14, the middle portion of which 75 bears against the rod 9 and the ends of which bear respectively against the arms 6. The arrangement and tension of the spring 14 is such that it will normally force the member 4 toward the door. 80

When the door is opened, it will pull against the rod 9 and member 12, thereby increasing the tension of the spring 14. Upon releasing the door, said spring will force the door to the initial closed position 85 shown in Fig. 2. If the door is swung to the fully open position, which may be effected, due to the flexibility of the connecting mechanism 9 and 12, the spring will still draw the door to the closed position, 90 the member 12 being of sufficient length to permit the rod 9 to have a straight pull upon the pin 7.

Owing to the hinge member 1 being attached to the door, near the middle thereof, 95 and owing to the hinge connection between the members 1 and 4, great leverage power is exerted by the device tending to close the door, and therefore, a relatively short and weak spring may be employed. 100

While I have shown and described my invention, as applied to a door, it will be obvious that it may be used for forcing other closures to the closed position.

I do not limit my invention to the structure shown and described, as modifications, within the scope of the appended claim, may be made without departing from the spirit of my invention. 105

What I claim is:—

In a door spring, a hinge comprising a swinging member having two arms, and a

member hinged to the swinging member and adapted to be secured to a door, a V-shaped anchoring member having a hook at the end of each arm, two screw eyes respectively pivotally engaging said hooks and adapted to be secured to a door jamb, a pin carried by the arms of said swinging member, a connecting member having two hooks respectively engaging said pin and said V-

shaped anchoring member, and a coil spring 10 encircling said pin and having its ends bearing respectively against the arms of said swinging member and having a middle portion bearing against said connecting member.

In testimony whereof I have signed my 15 name to this specification.

JAMES F. SWIFT.
